DESIGN FOR A VIBRATOR

Nels A. Nelson, Chicago, Ill., assignor to Raymond T. Moloney, Chicago, Ill.

Application November 27, 1939, Serial No. 88,493

Term of patent 7 years

To all whom it may concern:

Be it known that I, Nels A. Nelson, a citizen of the United States, residing at Chicago, in the county of Cook and State of Illinois, have invented a new, original and ornamental Design for a Vibrator, of which the following is a specification, reference being had to the accompanying drawing, forming a part thereof.

The drawing shows a three-quarter front perspective view of the vibrator showing my design. The other side of the vibrator is substantially like the side shown. The dominant features of my design reside in the portions shown in full lines.

I claim:

The ornamental design for a vibrator as shown, and described.

NELS A. NELSON.
